UNITED STATES PATENT OFFICE.

MICHAEL H. KURYLA, OF PARK CITY, UTAH, ASSIGNOR TO THE MERRILL COMPANY, OF SAN FRANCISCO, CALIFORNIA, A CORPORATION OF CALIFORNIA.

REMOVABLE CLOSURE.

1,345,862.

Specification of Letters Patent.

Patented July 6, 1920.

Original application filed July 29, 1916, Serial No. 106,563. Divided and this application filed January 16, 1917. Serial No. 142,623.

To all whom it may concern:

Be it known that I, MICHAEL H. KURYLA, a citizen of the United States, and a resident of Park City, in the county of Summit and 5 State of Utah, have invented certain new and useful Improvements in Removable Closures, of which the following is a specification.

This application is a division of the application Serial Number 106,563, filed by me upon July 29th, 1916.

The present invention relates to closures applicable to chambers of all sorts and to mechanism for removing and replacing such 15 closures. The mechanism which I have invented may readily be applied to the simultaneous opening and closing of closures at the opposite ends of a chamber, but it is also applicable to a single closure.

20 An object of my invention is to provide mechanism by which a closure may be released, swung out of the way, returned and locked in closed position.

A further object of my invention in its 25 preferred form is to effect the simultaneous moving and locking of two opposite closures.

To effect these purposes, I have provided a mechanism through which the various operations necessary in opening, moving out 30 of the way, returning and locking opposite closures are effected in proper order by manipulation of a single operating means. The turning of a hand-wheel effects successively the loosening of the closures, the movement of the closures directly away from the chamber and the swinging of the 35 closures out of line of the apertures which they normally close. A rotation of the hand-wheel in the reverse direction swings the closures into line with the openings, drawing them in toward and against the peripheries of the openings and locks them into close contact therewith.

40 For purposes of illustration, I have in the accompanying drawing shown the removable closures and mechanism comprising my present invention applied to a chamber containing filter-plates and constituting 45 with the closures a pressure filter. While my invention may be used with particular advantage in connection with a pressure-

filter, it should be clearly understood that the invention is by no means limited to this application. It may be used in connection 55 with any chamber used for any purpose whatever.

In the accompanying drawings—

Figure 1 is an end elevation of a filter-chamber parts being broken away showing 60 the closures in closed position.

Fig. 2 is a vertical cross-section of the filter-chamber showing the closures removed from the openings in the chamber.

Fig. 3 is a top view of the chamber with 65 the closures in closed position with a portion of the upper closure removed.

Fig. 4 is a side elevation, partly in section, of the filter-chamber with the closures 70 in closed position.

In the embodiment of my invention illustrated, a suitable frame 2 supports the chamber 3. The chamber is so constructed that it may be entirely open at top and bottom. When desired, the chamber is tightly 75 closed by the top and bottom closure-plates 34, 35. Joints between these plates and the chamber walls may be sealed by gaskets 36, seated in grooves in the chamber.

Arranged at each end of the filter is a bar 80 41, which, when the filter is closed, is vertically disposed. Each of the closure-plates 34, 35 is provided at its ends with elongated guides 38 through which the bars extend, the closures being arranged to slide on the bars 85 and the bars serving to hold the closures aligned. The bars are rotatably mounted at their centers, so that they may swing to allow the closures to be swung out of alignment with the openings in the filter-chamber. Arranged at each end of the filter is a frame 42, pivoted at one end on the horizontal shaft 43, which is journaled in the filter-frame, the opposite ends of the frames 42 being capable of vertical movement, 90 which movement is limited in the downward direction by a set-screw 44, which is attached to an abutment 45, on each end of the filter-frame (Figs. 1-3). This construction allows the frame to rock slightly about its 95 pivot for reasons which will be set forth hereinafter.

Journaled in each frame 42 at the center is a shaft 46, upon which is mounted a

gear 47, which is provided with a flanged hub 48. The bar 41 is journaled on the hub 48, and the friction between the hub and the bar tends to cause the bar to move with the hub. Rotation of the gear causes the bar to swing to move the closures 34 and 35 out of or into alignment with the openings in the filter-chamber. Arranged in the flanges 51 of the hub, at diametrically opposite points, are shafts 52, 53, to which are attached links 54, 55, which are attached at their other ends to the closures 35 and 34, respectively. The links are bent so that they pass around the hub and when the filter-chamber is closed, as shown in Fig. 1, the shaft 53, to which the links 55 of the upper closure 34 are attached, lies below the shaft 46; and shaft 52, to which the links 54 of the lower closure 35 are attached, lies above the shaft 46. Rotation of the gear-wheel 47, Fig. 1, in a counter-clockwise direction will cause shaft 52 to move downward and shaft 53 to move upward, lowering and raising, respectively, the closures 35 and 34. The gears 47 are rotated by the hand-wheel 56, secured to the shaft 43, to which shaft are secured pinions 57 meshing with the gears. The links 54 and 55 are bent to allow the shafts 52 and 53 to pass vertical alignment or dead center as the filter-chamber is being closed, thereby positively locking the closures to the chamber. After passing dead center, the links contact with the hub 48, which prevents their further rotation.

By virtue of the fact that the hub 48, to which the links are attached, is mounted in a vertically movable frame, the hub may move vertically to equalize the pressure on the top and bottom closures and to compensate for any small differences in link length. By employing an equalizing means, both closures are tightly and evenly pressed to their seats and an unequal link length will not prevent the proper seating of the closures.

The links 54, 55 are attached at their outer ends to eye-bolts 58 by means of pins 59. The outer ends or threaded portions of the eye-bolts 58 are disposed in the closures 34 and 35. Arranged on the outer and inner face of the closures and attached to the threaded portion of eye-bolts 58 are nuts 61 and 62, respectively. By the adjustment of these nuts on the eye-bolts 58 the effective length of the link is varied.

Means are provided for restraining the movement of the closures during the opening of the filter to a vertical movement until the closures have moved a sufficient distance from the filter-chamber to permit them to clear the chamber walls as they are swung to the sides thereof. Formed on each end of the frame 2, below the filter-chamber and to one side of the center line thereof is an abutment 65 (Fig. 2), which, when the filter

is closed, is engaged by the side of guide 38, which for this purpose projects beyond the operative face of the closure. The abutment lies on that side of the guide toward which the closure moves as it is swung from alignment with the chamber. When the closure has been moved vertically away from the chamber a sufficient distance to allow it to clear the chamber as it swings, the guide 38 has been moved out of contact with the abutment 65 and the frictional pull on the bar 41, due to the rotation of the gear 47, causes the bar to swing on its axis and carry the closures laterally, clear of the openings in the chamber. An abutment 66 (Figs. 2, 3) on the frame 42 stops the swinging movement of the closures by contacting with the bar 41. The filter-chamber is then completely open at the top and bottom.

When it is desired to close the chamber, the gear 47 is rotated in the opposite direction and the closures are moved back into alignment with the filter-chamber, being halted in the aligned position by abutments 69 (Figs. 2, 4) on the frame with which the guides 38 contact. The abutment 69 is placed lower than the abutment 65 and the guide 38 passes abutment 65 and strikes abutment 69. The frictional contact between the gears 47 and the bars 41 causes the bars to swing with the gears until the movement of the gears draws the closures in against the chamber and locks them in position. The frictional contact prevents the closures from being drawn together by the rotation of the gear until after they have passed the sides of the chamber and are in position to be seated.

I claim:

1. A chamber having opposite openings, closures for said openings, an actuator for said closures situated between them, means for drawing said closures toward said actuator, and a movable support for said actuator.

2. A chamber having openings in opposite walls, closures for said openings, a swinging frame between said closures, an actuator for said closures rotatably mounted on said swinging frame, links connecting said closures with said actuator.

3. A chamber having an opening, a closure for said opening, a rotatable actuator for said closure, means for moving said closure in alignment with said opening positively connected to said actuator, means for swinging said closure relative to said opening frictionally connected with said actuator.

4. A chamber having an opening, a closure for said opening, a rotatable actuator for said closure, means for moving said closure directly away from said opening positively connected to said actuator, means for swinging said closure frictionally connected to said actuator, a stop to prevent said clo-

sure from swinging until it has been moved directly away from the opening for a predetermined distance.

5. A chamber having an opening, a closure for said opening, a rotatable actuator for said closure, means for moving said closure directly toward said opening positively connected to said actuator, means for swinging said closure into alinement with said opening frictionally connected to said actuator, and a stop to prevent further swinging of said closure when brought in alinement with said opening.

6. A chamber having an opening, a closure for said opening, a rotatable actuator for said closure, means positively connected to said actuator for moving said closure in alinement with said opening, means frictionally connected with said actuator for swinging said closure out of and into alinement with said opening, a stop to prevent said closure from swinging out of alinement with said opening in one direction until it has been moved directly away from the opening for a predetermined distance, and a stop to prevent said closure from swinging out of alinement with said opening in the other direction.

7. A chamber having an opening, a closure for said opening, a rotatable actuator for said closure, a bar slidably connected with said closure and rotatable upon the same axis as the actuator and in frictional contact with the actuator.

35. 8. A chamber having an opening, a closure for said opening, a rotatable actuator for said closure, a bar pivoted on said actuator slidably connected with said closure,

and a link connected with said closure and pivoted at an eccentric point on said actuator.

9. A chamber having an opening, a closure for said opening, a rotatable actuator for said closure, a bar slidably connected with said closure and rotatable upon the same axis as said actuator and in frictional contact with said actuator, a link connected with said closure and pivoted at an eccentric point on said actuator.

10. A chamber having openings in opposite walls, closures for said openings, a bar on which said closures are slidable, links connected to said closures and arranged to slide them along said bar, and means for rotating said bar to shift said closures from alinement with the chamber openings.

11. A chamber, removable closures for the top and bottom of said chamber, a shaft extending alongside the chamber, a frame rotatably mounted on the shaft at each end of the chamber, a gear journaled in each frame, a bar pivoted on each frame and slidably engaging the closures, links connecting said closures to eccentric points on said gears and means for rotating said gears, whereby the closures are slid along said bars.

12. A chamber, opposite removable closures on said chamber, a revolvable carrier whose axis is parallel to said closures on which said closures are slidably mounted, and means for sliding said closures on said carrier and rotating the carrier to move the closures from alinement with the chamber openings.

MICHAEL H. KURYLA.
